(57) CLAIM

The ornamental design for a handheld storage device, as shown and described.

DESCRIPTION

FIG. 1 is a perspective view illustrating my design for a handheld storage device.

FIG. 2 is a front view thereof.

FIG. 3 is a rear view thereof.

FIG. 4 is a left side view thereof.

FIG. 5 is a right side view thereof.

FIG. 6 is a top plan view thereof.

FIG. 7 is a bottom plan view thereof.

FIG. 8 is a perspective view illustrating a portion of my handheld storage device without a cover.

FIG. 9 is a front view thereof.

FIG. 10 is a rear view thereof.

FIG. 11 is a left side view thereof.

FIG. 12 is a right side view thereof.

FIG. 13 is a top plan view thereof.

FIG. 14 is a bottom plan view thereof; and,

FIG. 15 is view showing my design for a handheld storage device with the cover removed.

The broken lines are for illustrative purposes only and form no part of the claimed design.
